UNITED STATES PATENT OFFICE.

FELIX McCARTHY, OF POTTSTOWN, PENNSYLVANIA.

BLOW-OFF VALVE.

SPECIFICATION forming part of Letters Patent No. 771,486, dated October 4, 1904.

Application filed February 18, 1904. Serial No. 194,248. (No model.)

To all whom it may concern:

Be it known that I, FELIX McCARTHY, a citizen of the United States, residing at Pottstown, in the county of Montgomery and State 5 Pennsylvania, have invented certain new and useful Improvements in Blow-Off Valves; and I do hereby declare the following to be a full, clear, and exact description of the invention, such as will enable others skilled in the art to 10 to which it appertains to make and use the same.

My invention has relation to what are termed "blow-off" valves; and it consists of certain novel features of construction and combination of parts, the preferred form 15 whereof will be hereinafter set forth, it being understood that I desire to comprehend such substantial equivalents and substitutes of the construction presented as may be regarded as falling fairly within the scope of 20 my invention.

My main object is to provide a valve of the character specified which will possess great power to resist deterioration and wear incident to the discharge of scale and grit from 25 the boiler, which in blow-off valves as now commonly constructed are discharged directly in contact with the valve-seat, thereby disintegrating said seat and utterly destroying its efficiency after a very limited use.

A further object of my invention is to so 30 mount my valve and valve-seat that the seat proper or the packing-ring carried thereby will be shunted from the path of discharge, and thereby protected from all wear and deterioration except that arising from the performance of its legitimate office of affording a gasket or packing between the valve and valve-seat proper.

Other objects and advantages will appear 35 from the following specification, which is supplemented by the accompanying drawings, made a part thereof, and in which—

Figure 1 shows a longitudinal sectional view of my improved blow-off valve disposed 40 in an open position. Fig. 2 is a similar view showing my valve in a closed position. Fig. 3 is a detail view in perspective of my valve proper, showing a portion of the valve-stem

broken away; while Fig. 4 is a plan-sectional view of my valve, taken on line 4-4 of Fig. 1. 50

In order that the various details of my invention, together with such coöperating accessories as may be deemed necessary to show a practical application thereof to use may be conveniently designated, numerals will be applied thereto, the same numeral referring to the same part in all the views, and, referring in detail to the parts of the drawings, 1 indicates a portion of a boiler to which my blow-off valve is attached substantially in the usual 60 manner, as by bolting the flange 2, carried by the body portion 3 of my valve, directly to the boiler, whereby the opening 4 in the latter will register with the bore of said valve-body. The bore or opening in my valve-body 3 extends entirely through the same, the outer end of said opening being closed by the head 5, said head being secured in position in the usual manner, as by the bolts 6.

The head 5 is also provided with a suitable 70 stuffing-box 7, through which extends the valve-stem 8, preferably forming an integral part of my valve 9, though it is obvious that said stem may be separately attached thereto, if desired. The inner end of the valve-body 75 is provided with the bushing 10, of brass or other non-rusting material, said bushing being designed to fit tightly within the bore of the valve-body and register directly with the opening 4 in the boiler. 80

It will be observed that the valve 9 is provided with an annular flange 11 at its upper end, said flange fitting snugly in the bore of the body-section 3 and is designed to be brought directly in engagement with the packing ring or gasket 12, resting partly upon the shoulder or valve-seat proper, 13, and partly upon the upper beveled edge of the bushing 10, as will be clearly observed by reference to Figs. 1 and 2. 85

I also form an annular groove or recess 14 in the lower end of the valve proper, 9, in which I dispose a suitable packing to prevent any leakage of steam between the bushing 10 and the valve, as will be obvious. 90

It will also be observed that the body por-

tion 3 is provided upon one side with the extension or neck 15, terminating in a flange 16, which latter is adapted to be bolted directly to the flange 17 of the discharge-pipe 18, leading to the sewer or other point where the discharge from the boiler is to be conveyed. The valve proper, 9, is provided with an aperture 19 upon that side directly opposite the throat or bore of the neck 15, whereby when 10 the valve is raised or disposed in an open position said aperture will be in direct registration with the bore of the neck and in position to convey the discharge directly into the discharge-pipe 18. When the valve is in an open 15 position, as will be observed by reference to Fig. 1 of the drawings, it will be seen that the flange 11 snugly fits the outer end of the bore of the body-section 3, thereby preventing the passage of steam, and consequently relieving 20 the head 5 from all pressure and, in fact, rendering it entirely unnecessary to provide the stuffing-box 7, inasmuch as it will be impossible for but little, if any, discharge to take place between the flange and the walls of the opening in which it is disposed.

It is obvious that in cases where the stuffing-box is to be wholly dispensed with a packing-ring (not shown) might be provided in the edge of the flange 11.

30 It will thus be seen that I have accomplished the object of my invention—namely, to prevent contact of the mud, sediment, scales, and other gritty substances carried by the discharging water and steam from coming in contact with the valve-seat, inasmuch as the discharge is passed directly out of the aperture 19 and thence into the discharge-pipe 18, the valve 12 in the meantime being wholly isolated and protected in the manner above set forth.

40 In order to place the movable part of my improved valve reliably under the control of the operator, I thread the outer end thereof and enter the same into engagement with the threaded bore of the bushing 20, which latter 45 is preferably formed of brass and is rotatably mounted in the cross-head 21, locked in engagement with the outer end of the body 3 of my valve, as by the columns 22 and 23. The bushing 20 is held rotatably in place in 50 its seat in the cross-head 21 by means of the set-screw 24, reaching into an annular groove formed in the outer surface of the bushing, as indicated by the dotted lines 25.

The valve proper, 9, and the valve-stem 8 55 are held against rotation by the cross-bar or guide 26, the ends of which are properly shaped to fit around a contiguous part of the columns or to extend into vertically-disposed recesses or grooves formed in the inner sides 60 thereof.

Obviously, therefore, my improved blow-off valve may be very quickly opened or closed by simply turning the controlling-wheel 27 in the proper direction.

It may be stated in this connection that the 65 life of a blow-off valve as now commonly constructed and wherein the discharge from the boiler is delivered more or less into direct contact with the valve-seat is comparatively very short, a very limited use necessitating renewal 70 of the packing-rings and other parts, whereas by actual test I have demonstrated the great importance and desirability of locating the valve-seat out of the path of the discharge from the boiler, and I therefore have called 75 special attention to the peculiar construction and combination of elements necessary to accomplish this desirable result.

Obviously certain changes in the arrangement of the parts herein described may be 80 made without materially departing from my invention, and believing that the advantages, construction, and manner of using my improved blow-off valve have thus been made clearly apparent further description is dis- 85 pensed with.

What I claim as new, and desire to secure by Letters Patent, is—

1. In a blow-off valve comprising a body portion having a longitudinal bore, a neck 90 upon one side thereof having a bore intersecting said longitudinal bore, a valve-seat in said body portion, a cylindrical bushing fixed within the lower end of said longitudinal bore and open at both ends, the upper end of said 95 bushing being beveled and extending slightly above said valve-seat, a gasket resting upon said valve-seat and beveled edge of said bushing, the extended end of said bushing serving to hold said gasket in place, a longitudinal cylindrical valve adapted to reciprocate within said longitudinal bore, said valve having an opening in one side thereof adapted to register with the bore in said neck when desired, an annular flange at the upper end of 100 said valve adapted to fit snugly in the upper end of said longitudinal bore, a valve-stem secured to said valve and means at the upper end thereof to raise and lower said valve, said 105 valve also having an annular recess in its lower end adapted to receive suitable packing, whereby a leakage of steam between said valve and bushing will be prevented, all combined substantially as set forth.

2. In a blow-off valve, the combination with 115 the body portion, having a longitudinal bore and a seat formed therein, of a cylindrical valve to fit said bore, a stem extending from the upper end of said valve, means carried by the body portion adapted to coöperate with 120 said stem to raise and lower said valve, said valve having an opening so located that when said valve is at its highest elevation said opening will register with a suitable opening in the side of said body portion and carry the 125 discharging contents entirely above and out of direct contact with said valve-seat, a cylindrical bushing fitting the lower portion of

said longitudinal bore and extending from the extreme lower edge thereof up and slightly above the valve-seat, said bushing being open at both ends and having its upper end disposed 5 at an oblique angle whereby a gasket will be securely held in place upon said seat, substantially as set forth.

In testimony whereof I have signed my name to this specification in the presence of two subscribing witnesses.

FELIX McCARTHY.
